SPARK PLUG GAP TESTER

John M. Porter, Fort Myers, Fla.

Application August 22, 1944, Serial No. 550,633

6 Claims. (Cl. 33—168)

1

This invention relates to a spark plug gap tester and more particularly to such a device of the "Go-No Go" type.

A primary object of this invention is the provision of an improved spark plug gap tester so arranged that the gap between the points of a multi-point spark plug may be readily tested with a minimum of time and a maximum of efficiency.

An additional object is the provision of such a tester embodying wires of different diameters, one of which is adapted to pass between the points, and the other of which is of a size adapted to be precluded from passing between the points when the points are properly set.

Another important object is the provision, in such a tester, of means for advancing the wire, when portions thereof are broken off in usage.

Still another important object is the provision of means whereby the retraction of the wire into the tube forming a part of the device, in such manner that the sharp end may dig into the walls of such a tube when the wire is pushed outwardly, is precluded.

Still further objects reside in the arrangements of parts, combinations of elements, and features of construction, all as will be more fully pointed out hereinafter and disclosed in the accompanying drawings, wherein there is shown a preferred embodiment of this inventive concept.

In the drawings:

Figure 1 is a side elevational view showing the device comprising the instant invention in use.

Figure 2 is a side elevational view of the device as viewed from one side.

Figure 3 is a side elevational view of the device as viewed from the opposite direction.

Figure 4 is a sectional view of the device shown in Figures 2 and 3 taken substantially along the center line.

Figure 5 is a perspective view of the device disclosing the operating wires.

Figure 6 is an enlarged sectional view taken substantially along the line 6—6 of Figure 2 as viewed in the direction indicated by the arrows, and

Figure 7 is an enlarged sectional view taken substantially along the line 7—7 of Figure 4.

Like reference numerals refer to like parts throughout the several views of the drawings.

Having particular reference now to the drawings, the tester of the instant device is comprised of a sleeve 10 having two right angularly disposed extending tubes 12 and 13 at one end. Sleeve 10 has a slide block 14 positioned therein having a

2

bore or hole 15 cut thereinto and an aperture suitably threaded to engage the threads of a set screw 16, the head 17 of which extends exteriorly of the tube through a slot 18. The ends of tubes 12 and 13 extend inwardly in the sleeve 10 and are suitably secured therein as by soldering, welding, or the like and form an abutment against which seats one end of a coiled spring 19, the other end of which is adapted to abut slide block 14.

Two wires 20 and 21, respectively, and of different diameters, for example, .011 inch diameter, and .014 inch diameter, respectively, are adapted to be passed inwardly through tubes 13 and 12 into sleeve 10 and engage in drilled hole 15, where their ends are secured in position by a set screw 16. Spring 19 serves to preclude the buckling of wires 20 and 21 outwardly through slot 18.

If desired, tubes 12 and 13 may be painted in different colors, as for example green and red, the smaller wire being passed through the green tube and the larger through the red tube, to indicate respectively their "Go" and "No Go" functions.

Referring now to Figure 6, there is provided in the base of slide 14 a recess or slot 25 within which is secured a wire 26 having an angularly bent tip 27. Tip 27 is adapted to engage in any selected one of a series of perforations 28 extending longitudinally of the tube on the opposite side thereof from groove 18.

From the foregoing the operation of the device should now be readily understandable. As above pointed out, suitable wires of different diameters are inserted through the tubes 12 and 13 and secured in block or slide 14 in the manner previously described. The ends of these wires are permitted to extend a suitable distance, normally comprising a small fraction of an inch and the device is held as indicated in Figure 1. The wires are then successively passed between the points 30 of a spark plug 31, the arrangement being such that if the plug points are properly spaced the smaller wire will pass therebetween and the larger wire will not. The diametrically opposed disposition of the two test wires facilitates ready rotation of the tester in the hand, and thus provide a relatively fast and efficient method of testing the gaps in spark plugs.

In such testing it frequently happens that the projecting portion of the wire will be broken off, in which case additional wire is fed from the interior of sleeve 10 by moving the slide block 14

forwardly in the slot 18. This is effected by forcing the point 27 of wire 26 out of its associated perforation 28 and moving the same up to the next perforation. These perforations are preferably spaced at a distance corresponding to the desired extending length of wire, and accordingly movement equivalent to one perforation will extend the wire, broken off adjacent the end of its associated tube, the required distance.

The engagement of wire 26 with the perforations 28, correspondingly precludes the inward passage of the wires back into their associated tubes, which is advantageous since in most instances the wires when broken leave a jagged edge which may engage in the interior wall of the tube, and result in a jamming of the device when it is desired to feed more wire outwardly therefrom.

From the foregoing it will now be seen that there is herein provided a new and useful spark plug gap tester accomplishing all the objects of this invention and many others including advantages of great practical utility and commercial importance.

As many embodiments may be made of this inventive concept, and as many modifications may be made in the embodiment herein shown and described, it is to be understood that all matter herein is to be interpreted merely as illustrative and not in a limiting sense.

I claim:

1. In a spark plug gap tester, in combination, a sleeve having a longitudinal row of perforations on one side thereof, tubes extending from said sleeve, a wire passed through each of said tubes into said sleeve, and extending outwardly therefrom, a block slidably mounted in said sleeve, means for securing the ends of said wires in said block, and means for securing said block against sliding movement in said sleeve, said means including a wire secured to said block and engageable in one of said perforations.

2. In a spark plug gap tester, in combination, a sleeve having a longitudinally extending slot on one side thereof and a longitudinal row of perforations on the other side thereof, tubes extending from said sleeve, a wire passed through each of said tubes into said sleeve, and extending outwardly therefrom, a block slidably mounted in said sleeve, means for securing the ends of said wires in said block, means for securing said block against sliding movement in said sleeve, said means including a wire secured to said block and engageable in one of said perforations, and means for moving said slide in said sleeve after said securing means are released, said means including a set screw extending outwardly from said block through said slot.

3. A tester for spark plug gaps comprising a body having a longitudinal chamber therein, a block slidably in said chamber, a compression spring in said chamber urging said block in one direction, conduits extending in different directions from said body and communicating with said chamber, gauge elements of different sizes slidably guided in said conduits and secured at their inner ends to said block for selective extrusion from and retraction into said conduits by

movement of said block, said body having longitudinally spaced apertures in one side thereof and a detent on said block engageable in said apertures for securing said gauge elements in adjusted position relative to said conduits.

4. A tester for spark plug gaps comprising a body having a longitudinal chamber therein, a block slidable in said chamber, a compression spring in said chamber urging said block in one direction, conduits extending in different directions from said body and communicating with said chamber, gauge elements of different sizes slidably guided in said conduits and secured at their inner ends to said block for selective extrusion from and retraction into said conduits by movement of said block, said body having longitudinally spaced apertures in one side thereof and a detent on said block engageable in said apertures for securing said gauge elements in adjusted position relative to said conduits.

5. A tester for spark plug gaps comprising a body having a longitudinal chamber therein, a block slidable in said chamber, a compression spring in said chamber urging said block in one direction, conduits extending in different directions from said body and communicating with said chamber, gauge elements of different sizes slidably guided in said conduits and secured at their inner ends to said block for selective extrusion from and retraction into said conduits by movement of said block, said body having longitudinally spaced apertures in one side thereof and a detent on said block engageable in said apertures for securing said gauge elements in adjusted position relative to said conduits, said block having a recess on the side adjacent the apertures, said detent being mounted in said recess and being movable therefrom laterally of said block for engagement and release from the apertures.

6. In a spark plug gap tester, in combination, a sleeve having a longitudinal row of perforations on one side thereof, tubes extending from said sleeve, a wire passed through each of said tubes into said sleeve, and extending outwardly therefrom, a block slidably mounted in said sleeve, means for securing the ends of said wires in said block, and means for securing said block against sliding movement in said sleeve, said means including a wire secured to said block and engageable in one of said perforations, a coil spring in said sleeve surrounding said wires to preclude buckling of the wires.

7. In a spark plug gap tester, in combination, a sleeve having a longitudinal row of perforations on one side thereof, tubes extending from said sleeve, a wire passed through each of said tubes into said sleeve, and extending outwardly therefrom, a block slidably mounted in said sleeve, means for securing the ends of said wires in said block, and means for securing said block against sliding movement in said sleeve, said means including a wire secured to said block and engageable in one of said perforations, a coil spring in said sleeve surrounding said wires to preclude buckling of the wires, said coil spring abutting said block.
